PIRN CAP

This invention is concerned with a tubular pirl on which filamentary material of indefinite length such as textile yarn, thread, roving, tow, cord, twine, or the like is wound for transportation and dispensing.

A pirl is a hollow metal cylinder typically 2 inches in diameter and somewhat more than a foot in length. To provide a suitable surface, the metal cylinder may be provided with an external shrink fitted phenolic plastic sleeve. The plastic sleeve may be provided with a surface finish of fine circumferential grooves to reduce axial slipping of the yarn on the pirl. The plastic sleeve extends around one end of the cylinder to provide a smoothly rounded surface at that end. This end is commonly called the nose and is the end of the pirl from which the yarn is drawn in a direction generally parallel to the pirl axis as the yarn is used. The other end of the pirl is commonly called the tail and is the end by which the pirl is held when the pirl bearing a yarn supply is placed in the machine which uses the yarn.

When the yarn supply has been exhausted from a pirl, the empty pirl is removed from the yarn using machine and is replaced by another pirl having a new supply of yarn. The empty pirl is returned to the yarn manufacturer who winds a new supply of yarn on the pirl. The plastic covering on the nose of the pirl must be free of nicks, dents, or abrasions because such irregularities would interfere with the feeding of the yarn as the yarn is run off or drawn over the nose of the pirl during use.

The nose of the pirl is particularly prone to impact damage during storage and return shipment of the empty pirls to the yarn manufacturer because the empty pirl has no yarn to serve as a cushion. The ends of empty pirls are more exposed to impact damage than is the cylindrical surface. While damage to the tail of the pirl is not particularly significant, damage to the nose affects the freedom with which the yarn runs across the nose as the yarn is drawn from the pirl during use. Damage to the nose of the pirl has heretofore necessitated removal and replacement of the shrink fitted plastic sleeve.

The present invention prevents damage to the pirl nose, permits the continued use of pirls having previously damaged noses, and permits easy replacement of a damaged nose portion by providing a readily replaceable cap ring which serves as the nose of the pirl. The replaceable cap ring improves the uniformity of runoff characteristics over pirls not provided with the ring of the present invention.

The drawing is a view partially in section of a pirl fitted with the cap ring of the present invention.

Referring now to the drawing, the pirl comprises a hollow metal cylinder 10 having a plastic end plug 12 frictionally held in the nose end of the pirl. End plug 12 is provided with an outer circumferential rounded edge 14. A plastic sleeve 16 is shrink fitted about the cylindrical exterior of the pirl tube 10 and about the nose end of the pirl tube and the circumferential edge 14 of the end plug 12. The resulting radius of the end of the plastic sleeve 16 constitutes the surface of the nose of the pirl. It is this surface which is prone to damage that affects the usefulness of the pirl.

The present invention adds to this conventional pirl construction a plastic cap ring 20 which fits over the nose portion

of the pirl and is retained thereon by friction. The ring 20 may be molded from flexible plastic such as polyethylene thereby rendering the ring resistant to permanent impact damage in the form of nicks or dents. Alternatively, the ring may be molded of a phenolic similar to that employed in the sleeve 16. In either case, the ring 20 is easily replaced when damaged. The cap ring 20 may be molded in identifying colors which are indicative of the nature of the yarn supplied on the pirl.

The exterior shape of the ring 20 includes a smooth rounded portion 21 against which the yarn bears during runoff. A tapered conical surface 22 is merged with the rounded surface 21 at the upper end and with the cylindrical surface of the pirl at the end remote from the nose to extend the protection afforded by the ring 20 over a considerable portion of the cylindrical surface near the nose of the pirl. The taper of surface 22 insures that the yarn being run off has only minimal contact with the ring at the rounded surface 21 to reduce friction.

The ring 20 stands proud of the cylindrical exterior surface of the pirl by having an outer diameter substantially greater than that of the cylinder to preserve the desirable minimum of contact as the yarn supply is exhausted to the last windings in contact with the pirl surface. This greater diameter prevents the yarn from being drawn along the cylindrical surface of the pirl to thereby maintain substantially uniform the frictionally drag of the yarn as it runs off the pirl.

The ring 20 can be used on pirls having previously damaged nose portions to thereby render them serviceable without the need to replace the plastic sleeve 16. Further, the ring 20 tends to reduce pirl damage because it reduces the contact among empty pirls during storage and shipment. Empty pirls provided with the ring of the present invention can be stacked for storage and shipment with adjacent pirls reversed in respect to each other such that the rings 20 completely prevent contact of adjacent cylindrical surfaces. Any damage which may occur to the nose of the pirl occurs on the surface of the ring 20 rather than on the body of the pirl proper. The ring is readily replaceable. When the ring 20 is made of flexible plastic, permanent damage to the nose surface of the pirl is greatly reduced.

I claim:

1. A pirl for receiving, storing and delivering a wound supply of filamentary material comprising; a hollow tube having a hard nonmetallic layer extending substantially over the entire exterior surface of and extending over the nose end of the tube, an end plug affixed in the interior of the nose end of the tube, and a replaceable resilient molded plastic ring friction fitted over the nose end of the tube and extending over the portion of the tube exterior proximate the nose end, said ring having an exterior diameter greater than that of the proximate portion of the tube so as to stand proud of the tube, the portion of the ring exterior surface which overlies the nose end being rounded to provide a smooth bearing surface for contact by the filamentary material as it is drawn from the nose end of the pirl, the portion of the ring exterior surface which overlies the exterior surface of the tube being a transition in the form of a gradual conical taper between said rounded surface and said tube exterior, the interior surface of the ring having a substantial area for frictional retention of the ring on the exterior surface of the tube.
